PIVOTED CHAMBER WEAPON

John F. O'Brien, Springfield, Mass., assignor to the United States of America as represented by the Secretary of the Army

Application August 18, 1955, Serial No. 529,365

9 Claims. (Cl. 89—155)

(Granted under Title 35, U. S. Code (1952), sec. 266)

The invention described herein may be manufactured and used by or for the Government for governmental purposes without the payment of any royalty thereon.

My invention relates to guns having barrels with corresponding cartridge discharge chambers movable for charging, and more particularly to such a gun in which the chambers are laterally pivoted for displacement between individual firing and charging stations.

In a gun having separate cartridge chambers with an actuator for displacing the chambers, the rate of fire is limited by the stroke of the actuator, and the actuator stroke is directly proportionate to the displacement of the chambers. Accordingly, it is an object of my invention to provide such a gun requiring minimum charging displacement of the chambers.

Another object of my invention is to provide such a gun having peripherally notched barrels and laterally pivoted chambers for minimum charging displacement thereof.

A further object of my invention is to provide such a gun having chambers disposed for minimum charging displacement to achieve maximum rate of fire of the gun.

Other aims and objects of my invention are evident from the following explanation.

In carrying out my invention, a recoil unit for a gun includes barrels with corresponding peripheral breech notches, and cylindrical chambers. An actuator is disposed for reciprocal operation responsive to discharge of the gun, and each of the chambers is disposed to pivot about a lateral axis between a firing and a charging station in respective axial alignment with a particular one of the barrels and the notch thereof, responsive to the reciprocal operation. Each of the chambers is provided with a breech block slidable between closed and open positions respectively corresponding to the firing and charging stations of the chamber, and the breech block includes a firing device for closed position engagement with a cartridge disposed in the chamber for discharge thereof.

For a more complete understanding of my invention reference is directed to the following description and the accompanying drawings, in which:

Fig. 1 is an elevation of a single barrel weapon incorporating my invention with the chamber in the firing station thereof;

Fig. 2 is a view similar to Fig. 1 with the chamber in the charging station;

Fig. 3 is a view along line 3—3 of Fig. 1;

Fig. 4 is a view along line 4—4 of Fig. 2;

Fig. 5 is a view of the actuator shown in Fig. 1;

Fig. 6 is a perspective view of a twin-barreled weapon incorporating my invention with the left chamber in firing station; and

Fig. 7 is a partial plan view of the twin-barreled weapon.

Accordingly, a gun 12 with a recoil unit 14, includes a barrel 16 having peripheral breech notch 18, and a device includes a discharge chamber 20 pivoted about a lateral axis 22 between firing and charging stations in respective axial alignment with barrel 16 and notch 18, as in Figs.

1 and 2, respectively. Notch 18 is provided to limit the required charging displacement of chamber 20 to a minimum.

An indexing mechanism includes an actuator 24 axially slidible in recoil unit 14, and biased to a battery position, by a spring 26.

Recoil unit 14 includes a discharge gas piston 27 of the indexing mechanism, and actuator 24 includes a track 28 similar to the track in Fig. 5 for engagement with a follower 29 on chamber 20 for operation of actuator 24 in rearward and forward strokes to cycle chamber 20 between the firing and charging stations, responsive to discharge of a cartridge chambered in the battery station.

Gun 12 is provided with a feeder 30 for supplying cylindrical cartridges 32 to a position adjacent the charging station and in axial alignment therewith, and a rammer 34 separately operable for engagement with a live cartridge in the adjacent position to propel the cartridge into chamber 20, responsive to the forward stroke of actuator 24. Simultaneously, a case 40 of a discharged cartridge is propelled from chamber 20 into notch 18 for ejection of the case from the gun. A member 42 of recoil unit 14 is provided with a surface for engagement with case 40, to stop the live cartridge in chamber 20.

In Fig. 6, a gun 12 with a recoil unit 14 includes twin barrels 16 mounted thereon and provided with peripheral breech notches 18. The recoil unit is provided with devices including corresponding cylindrical chambers 20 pivoted about a single lateral axis 22.

The twin-barreled gun is provided with an indexing mechanism including an actuator 24 disposable in forward and rearward positions respectively corresponding to the firing stations of chambers 20, and axially slidible for rearward and forward stroke operation in recoil unit 14 respectively responsive to operation of a gas piston 27 of the indexing mechanism by means of gases from the discharge of cartridges in chambers 20. Actuator 24 includes a pair of similar cam tracks 28 for engagement with followers 29 on chambers 20 as shown in Figs. 6 and 7, to alternately disposed the chambers in individual firing and discharge stations in respective axial alignment with barrels 16 and notches 18, responsive to the operation.

Gun 12 is provided with a pair of feeders 30 and separately operated rammers 34, respectively, for supplying cartridges to the chambers and for propelling the cartridges into the chambers in the charging stations, responsive to the operation. Stop surfaces 42 are also provided for each of the chambers.

A block 44 including an electric firing device is slidably disposed in the breech of each chamber 20 and forked cam members 46 are laterally pivoted on recoil unit 14 for engagement with pins 48 on each chamber 20. Arms 50 of the members respectively engage blocks 44 for displacement thereof to closed and open positions respectively responsive to displacement of chambers 20 to the firing and charging station thereof for discharge of the cartridges chambered in the firing station.

It is readily appreciated from the above explanation that the actuator may be of light construction since it is required to transmit merely enough energy for displacement of the chambers between the firing and charging stations and to operate the breech blocks. Also, minimum displacement of the chamber is required for charging, resulting in minimum stroke operation of the actuator and consequent maximum rate of fire of the gun.

Although a particular embodiment of the invention has been described in detail herein, it is evident that many variations may be devised within the spirit and scope thereof and the following claims are intended to include such variations.

I claim:

1. A gun comprising a recoil unit including a barrel,

a device with a chamber transversely pivoted for displacement thereof between stations including a firing station for axial alignment of said barrel and said chamber for discharge of cartridges therein and a station for charging the cartridges in said chamber, and an indexing mechanism including a discharge gas piston and an actuator in engagement therewith disposed for rearward and forward operation responsive to the discharge, said device being disposed to engage said actuator for reciprocation of said chamber between said stations, responsive to the operation. 10

2. A gun comprising a recoil unit including a barrel, a device with a chamber transversely pivoted for displacement thereof between a pair of stations including a firing station for axial alignment of said barrel and said chamber for discharge of cartridges therein and a station for charging the cartridges into said chamber, an actuator spring-biased to a battery position and a piston disposed for battery position engagement with said actuator for rearward and forward operation responsive to the discharge, said chamber engaging said actuator for reciprocation between said stations responsive to the operation. 15

3. A gun as in claim 2 with a cam and a corresponding follower respectively disposed on said actuator and said device for the reciprocation responsive to the operation. 20

4. A gun as described in claim 2 with a block slidably disposed in said device and a member pivoted in said recoil unit to engage said device and said block for displacement thereof to and from a position inclosing the breech end of said chamber respectively for the discharge and the charging responsive to the reciprocation. 30

5. A gun as in claim 2 with said chamber disposed for inclosing cylindrical cartridges, said barrel provided with a peripheral notch in the butt end thereof, and said charging station disposed adjacent said notch for ejection of the cases of the cartridges thereto responsive to the 35 charging for minimum displacement of the reciprocation.

6. A gun comprising a recoil unit, twin barrels therein,

devices including chambers for cartridges transversely pivoted between respective pairs of stations including firing stations in respective axial alignment with said barrels for alternate discharge of cartridges therethrough and stations for charging cartridges into said chambers, and an indexing mechanism including a gas piston and an actuator in said recoil unit disposed for rearward and forward stroke operation of said piston responsive to the discharge, said devices being engageable with said actuator, for reciprocation of said chambers between said pairs of stations responsive to the operation. 10

7. A gun as in claim 6 with cams and corresponding followers respectively disposed on said actuator and said devices for the reciprocation, responsive to the operation. 15

8. A gun as described in claim 6 with blocks respectively slidably disposed in said devices, and members pivoted in said recoil unit to respectively engage said devices and said blocks for alternate displacement thereof to and from positions inclosing said chambers respectively, for the discharge and charging, responsive to the reciprocation. 20

9. A gun as in claim 6 with said chambers disposed to inclose cylindrical cartridges, said barrels respectively provided with peripheral notches in the butt ends thereof and said charging stations disposed adjacent said notches for ejection of the cases of the cartridges therein responsive to the charging for minimum displacement of the reciprocation. 25
